UNITED STATES PATENT OFFICE.

FRANK R. McBERTY, OF EVANSTON, ILLINOIS, ASSIGNOR TO WESTERN ELECTRIC COMPANY, OF CHICAGO, ILLINOIS, A CORPORATION OF ILLINOIS.

DESIGN FOR A TELEPHONE-SWITCHBOARD CASING.

No. 38,027.

Specification for Design.

Patented May 22, 1906.

Application filed March 26, 1906. Serial No. 308,184. Term of patent 14 years.

To all whom it may concern:

Be it known that I, FRANK R. McBERTY, a citizen of the United States, residing at Evanston, in the county of Cook and State of Illinois, have invented a new, original, and ornamental Design for Telephone-Switchboard Casings, of which the following is a specification, reference being had to the accompanying drawing, forming part thereof.

The figure is a perspective view of a tele-

phone-switchboard casing, showing my new design.

I claim—

The ornamental design for a telephone-switchboard casing, as shown.

FRANK R. McBERTY.
